(57) **CLAIM**

The ornamental design for a toy ship as shown and described.

DESCRIPTION

FIG. 1 is a first perspective view of the top, front, and left sides of a toy ship showing my new design; FIG. 2 is a second perspective view of the top, rear, and right sides thereof;

FIG. 3 is a front view thereof;

FIG. 4 is a rear view thereof;

FIG. 5 is a top plan view thereof;

FIG. 6 is a right side view thereof; and,

FIG. 7 is a left side view thereof.

The broken lines shown are included for the purpose of illustrating portions of the article which form no part of the claimed design.

The bottom view is flat and devoid of surface ornamentation and has therefore been omitted from the drawings.
